FIREPLACE ACCESSORY

Philip M. Kalmis, Long Island City, N. Y.

Application March 24, 1939, Serial No. 263,900

13 Claims. (Cl. 219—43)

This invention relates to fireplace accessories. An object of this invention is to provide a highly attractive and useful fireplace accessory, consisting of a kettle mounted on a tray, having an electric heater and suspended by chains from a hinged adjustable bracket attached to the side of the fireplace, the construction being such that the kettle can be removed after the water boils and may be set on a table if desired.

10 A further object of this invention is to provide in a unit of the character described, an adjustable bracket so constructed that the kettle and tray may be suspended in any desired position in the fireplace, and may be readily swung away from the fireplace, so that the kettle may be the more easily removed from the tray.

15 A still further object of this invention is to provide in a unit of the character described, a tray provided with transparent or colored translucent plates beneath the kettle, so that light from the fireplace may illuminate the kettle.

20 Still another object of this invention is to provide a neat, rugged and durable fireplace accessory of the character described, which shall be relatively inexpensive to manufacture, attractive in appearance, easy to adjust and manipulate, and yet practical and efficient to a high degree in use.

25 Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

30 In the accompanying drawing, in which is shown various possible illustrative embodiments of this invention,

35 Fig. 1 is a front elevational view of a fireplace accessory embodying the invention, with parts in cross-section;

Fig. 2 is a bottom plan view of the tray;

40 Fig. 3 is a top plan view of the tray with the kettle removed;

Fig. 4 is a top plan view of the bracket shown in Fig. 1; and

45 Fig. 5 is a side elevational view of a bracket embodying the invention, and illustrating a modified construction.

50 Referring now in detail to the drawing, 10 designates a fireplace accessory embodying the invention installed in a fireplace 12. The fireplace 12 may be of any usual construction, having a front vertical wall 13 surrounding the fire-

place opening, and interior side walls 13a. The fireplace may be provided with electrically lighted logs or other illuminating means at the bottom of the fireplace, not shown. Such electric illuminating means are well known and sometimes simulate burning coals or embers.

55 The accessory 10 comprises a bracket 14 which may be attached to an inner wall 13a of the fireplace. The bracket 14 comprises a flat vertical plate 15 formed with openings 16 to receive 10 screws or other attaching devices 17, for attaching the brackets to the wall of the fireplace.

Extending from the plate 15 is a horizontal tubular member 18. Slidably extending in the 15 tubular member 18, is a horizontal rod 19 formed with an eyelet or opening 20 at its outer end. Mounted on the rod 19 is a hanger 21 comprising a vertical upwardly extending screw 22, extending through the eyelet or opening 20. At the 20 lower end of the screw 22 are a plurality of downwardly and inwardly curved hooks 23. On the screw 22 is a wing nut 24, for attaching the hanger to the rod 19.

25 Attached to the hooks 23 are the upper ends 25 of a plurality of chains 25. Any number of hooks 23 and chains 25 may be provided, although it is preferable to have three hooks and three chains. The lower ends of the chains 25 are attached to a tray 30, described in detail 30 hereinafter. The tray 30 comprises a central, annular, cylindrical member 31 having an annular, inwardly extending bottom flange 32.

35 The cylindrical member 31 is open at the top, and has a cut-away portion 31a. Integrally formed with said cylindrical member 31, are a plurality of similar, radial, horizontal arms 36 having downwardly stepped, outwardly extending portions 38 at the outer ends thereof. The portions 38 of the arms 36 are formed with 40 vertical through openings 39 to receive eyelets 39a, to which are connected the lower ends of the chains 25.

45 On the arms 36 is a flat horizontal plate 40 of glass or other translucent or transparent, preferably colored material. The plate 40 has a central opening 41 to receive the upper portion of the cylindrical member 31. Mounted on the outwardly extending portions 38 of the arms 36, is a flat annular ring 45 of glass or the like 50 transparent or translucent colored material.

55 Lemons or other articles may be placed on the annular ring 45. Said ring 45 has an upwardly extending bead 45a at its outer periphery to retain articles placed thereon from falling off.

Within the cylindrical member 31 is an electric heating unit 47 of usual construction, provided with a pair of radial extending prongs 48 projecting through cut-out 31a, to receive an electric socket of a cord connector.

5 Removably mounted on the cylindrical member 31 is a metal kettle or other receptacle 50, having a groove 51 to receive the upper end of the cylindrical member. The kettle 50 has a flat bottom wall or base 52 projecting into said cylindrical member and substantially contacting the heater 47. The kettle may be removed from the cylindrical member after water therein is heated or boils, and placed on a table.

10 15 It will be noted that electric lights or other illuminating means at the bottom of the fireplace will throw light upwardly through plates 40, 45, to illuminate the kettle. The colored plates 40 and 45 will produce highly attractive illuminating effects.

20 The position of the hanging unit may be adjusted by pulling the rod 19 outwardly to any desired position.

25 In Fig. 5 there is shown a bracket 60 illustrating a modified construction, attached to a wall of the fireplace. The bracket 60 has horizontal arms 61, and pivotally mounted on said arms, is a member 62 having a horizontal arm 63. Received on the arm 63 is a tubular member 30 64. The tray and kettle may be supported from the outer end of the tubular member 64 in any suitable manner.

35 It will now be noted that the tray and kettle may be swung about a vertical axis, and also moved outwardly due to the sliding action between the member 63 and 64, to adjust the position of the kettle and tray as desired.

40 45 The kettle is provided with a plurality of spaced eyelets 70 at the top. If desired the lower ends of the chains may be detached from the tray and connected directly to the eyelets 70, so that the kettle may be suspended without the tray.

50 It will thus be seen that there is provided a device in which the several objects of this invention are achieved, and which is well adapted to meet the conditions of practical use.

55 As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In combination, a member adapted to be fixed to a fireplace, a member pivoted thereto about a vertical axis, and having a horizontal arm, a member slidably mounted on said arm, chains attached to said second member, a horizontal tray supported on said chains, an electric heating element on the central portion of the tray, and a vessel removably mounted on said tray and over said heating element.

2. A tray comprising a central cylindrical portion, and radial arms extending therefrom, an electric heating element within said cylindrical portion, a light transmitting plate mounted on said arms and having a central opening to receive said cylindrical portion, and a vessel removably mounted on said tray, over said electric heating element, and having means to engage said cylindrical portion.

75 3. In combination, a tray having a central

cylindrical portion, and radial arms extending therefrom, a light transmitting annular plate on said arms, and having an upwardly extending bead at its outer periphery, a vessel having a portion receiving the central cylindrical portion 5 of the tray, and a heating element within said cylindrical portion of the tray, and beneath said vessel.

4. In combination, a bracket adapted to be attached to a wall, and having a horizontal portion, a member slidably mounted on said horizontal portion, a hanger on said member, a tray, means for suspending said tray from said hanger, said tray being formed with a central cylindrical portion, an electric element within said portion, 10 a vessel on said tray, and having means to engage said cylindrical portion, and covering said heating element.

5. In combination, a bracket adapted to be attached to a wall, and having a horizontal portion, a member slidably mounted on said horizontal portion, a hanger on said member, a tray, means for suspending said tray from said hanger, said tray being formed with a central cylindrical portion, an electric heating element within 15 said portion, a vessel on said tray, and having means to engage said cylindrical portion, and covering said heating element, and a light transmitting plate on said tray.

6. In combination, a bracket adapted to be 20 fixed adjacent the fireplace, a member slidably mounted on said bracket, a member suspended from the first member, and provided with an electric heating element, and a vessel removably mounted on the second member, and over said 25 heating element.

7. In combination, a bracket adapted to be fixed adjacent the fireplace, a member slidably mounted on said bracket, a member suspended from the first member, and provided with an 40 electric heating element, a vessel removably mounted on the second member, and over said heating element, and a light transmitting plate on said second member and below said vessel.

8. A tray having a central cylindrical portion, 45 and radial arms extending therefrom, an electric heating element within said portion, a light transmitting plate mounted on said arms, and having a central opening to receive said cylindrical portion, said radial arms having downwardly stepped, outwardly extending outer end portions, an annular ring of light transmitting material on said outer end portions of said arms, and a vessel removably mounted on the cylindrical portion of said tray, and over said heating 50 element, and having means to engage said cylindrical portion.

9. In combination, a member having a central chamber, and portions extending outwardly from said central chamber, an electric heating element 60 within said chamber, a vessel mounted on said chamber, and over said heating element, and light transmitting members on said outwardly extending portions, and below said vessel.

10. In combination, a tray comprising a frame, 65 an electric heating element thereon, a light transmitting plate on said frame, and a vessel removably supported on said frame and over said heating element, and above said plate.

11. In combination, a tray comprising a frame, 70 an electric heating element thereon, a light transmitting plate on said frame, a vessel removably supported on said frame and over said heating element, and above said plate, a bracket, and means interconnecting said bracket with 75

said tray to suspend said tray from said bracket.

12. In combination, a member adapted to be attached to a fireplace, chains attached thereto, a tray supported on said chains, an electric heating element on said tray, and a vessel removably mounted on said tray.

13. In combination, a member adapted to be

attached to a fireplace, chains attached thereto, a tray supported on said chains, an electric heating element on said tray, a vessel removably mounted on said tray, and a light transmitting plate on said tray and below said vessel. 5

PHILIP M. KALMIS.
